CLAIM

We claim the ornamental design for an aqueous parts cleaner, as shown and described.

DESCRIPTION

FIG. 1 is a perspective view of an aqueous parts cleaner showing our new design;

FIG. 2 is a front elevation view thereof;

FIG. 3 is a side view thereof;

FIG. 4 is an opposite side view thereof;

FIG. 5 is a top plan view thereof;

FIG. 6 is a bottom plan view thereof; and,

FIG. 7 is a rear elevation view.

The broken line showing of design details in FIGS. 1-7 is included for the purpose of illustrating portions of the aqueous parts cleaner and forms no part of the claimed design.
